W. B. TUNSTALL

WASHING APPARATUS

Filed May 19, 1922

UNITED STATES PATENT OFFICE.

WILLIAM B. TUNSTALL, OF WORCESTER, MASSACHUSETTS.

WASHING APPARATUS.

Application filed May 19, 1922. Serial No. 562,080.

To all whom it may concern:

Be it known that I, WILLIAM B. TUNSTALL, a citizen of the United States, residing at Worcester, in the county of Worcester 5 and State of Massachusetts, have invented new and useful Improvements in Washing Apparatus, of which the following is a specification.

This invention relates to apparatus for 10 cleansing a charge of fabrics immersed in water in a tub, by forcing air into the bottom portion of the tub, and allowing the air to pass upwardly through the charge.

The invention is embodied in certain improvements hereinafter described and claimed, in apparatus of this character, whereby an apparatus of marked simplicity and efficiency is provided, the nature of said improvements being such that the apparatus 15 is particularly adapted for use with an ordinary set tub having an inclined front wall, although the invention is not limited to an apparatus thus adapted.

Of the accompanying drawings forming 20 a part of this specification,—

Figure 1 is a front elevation, showing a set tub and a washing apparatus embodying the invention applied thereto.

Figure 2 is a section on line 2—2 of Figure 1.

Figure 3 is a section on line 3—3 of Figure 2.

Figure 4 is a section on line 4—4 of Figure 2.

Figure 5 is a section on line 5—5 of Figure 2.

Figure 6 is an enlargement of a portion of Figure 5.

The same reference characters indicate 40 the same parts in all of the figures.

The apparatus comprises a platform formed as a cover adapted to be supported on and to close the mouth of a tub 13, which as here shown, is a set tub of ordinary form.

45 The platform and the component parts of the apparatus hereinafter described, may, however, be adapted to cooperate with a tub of any suitable form. The platform may rest on the upper edges of the end and front walls of the tub, and may be fixed thereto.

The platform includes a body portion or section 12 provided with an opening 12^a, indicated by dotted lines in Figure 5, and a displaceable section or cover 12^b, which may 55 be connected by hinges 14 to a back ear on the body section, or otherwise adapted to

cover and expose the opening 12^a. The area of the opening 12^a is sufficient to permit the insertion and removal of fabrics when the section 12^b is displaced. Said opening is 60 preferably arranged to permit water from the usual faucets to enter the tub.

Supported by and above the platform 12 is an air-forcing means, including an electric motor 15, and a centrifugal fan 16, fixed 65 to the motor shaft 17. The fan is enclosed in a casing 18, the outlet 19 of which extends downwardly through the platform and constitutes an element of air-conducting means 70 fixed to the platform and including said outlet, a vertical flow conduit 20, extending nearly to the bottom of the tub and a return conduit 25, adapted to conduct air upward from the upper portion of the tub. Said platform and the air-forcing and air-conducting means fixed thereto are applicable 75 as a unit to a tub. The apparatus comprises also a clothes support composed of a foraminous substantially horizontal top portion 21, and a marginal curb 22, adapted to 80 rest on the bottom of the tub. The top portion 21 is flat, and preferably composed of sheet metal having numerous perforations 23. A woven wire or other screen 21^a, having openings smaller than the perforations 23, may be placed on the top portion 21. The flow conduit 20 has a sliding fit in the top portion 21, so that the apparatus may 85 be conveniently adjusted to the depth of the tub.

The area of the top portion 21 is such that it is adapted to support a charge of clothes between the platform and the bottom of the tub, so that air forced through the flow conduit passes upwardly in a multiplicity of streams, or bubbles through the charge. The air is returned from the upper portion of the tub to the fan casing by the return conduit 25, which is preferably elbow-shaped, having an intake end in the platform 12, and a discharge end communicating with the fan casing, as shown by Figures 2 and 5. The return conduit may be composed of sections connected by a sleeve 26, adapted to slip on the sections.

The apparatus includes a screen 27 attached to and movable with the displaceable section or cover 12^b. Another like screen 28 may be attached to the body section 12, as shown by Figure 3. The screens 90 may be made of woven wire. They prevent 95 the fabrics from rising to the platform, and 100

the screen 28 prevents the fabrics from obstructing the intake of the return conduit 25. The area occupied by the screens may be greater than that of the air-distributing 5 support, so that as shown by Figure 2, the screens and the support conform to the interior of a tub having an inclined front wall. When the apparatus is operated, air forced by the fan passes downward through 10 the flow conduit 20, and then upward through a charge contained in the tub, and is returned to the fan casing by the return conduit 25. The air in its upward passage through soapy water in which the fabrics 15 are immersed, forms a multiplicity of bubbles, which naturally accumulate in the upper portion of the tub. Some of this accumulation or froth is sucked up into the fan casing through the return conduit 25 20 and is carried downward by the air through the flow conduit 20. The motor 15 is located outside the path in which the air is circulated through the conduits 20 and 25, and is elevated above the platform, so that 25 liquid in the form of froth sucked up through the return conduit, cannot enter and short circuit the motor. To provide for the disposal of a part of the froth, I provide a standpipe 30, which may be detachably 30 connected at its lower end with the usual waste pipe 31. The upper or intake end of the standpipe is below the platform and above the lower portion of the screen 27. The standpipe provides a safety valve 35 whereby any excess pressure that may accumulate in the tub is released into the waste pipe. In other words, the standpipe prevents the accumulation of froth from upsetting the balance of pressure between the intake and the exhaust or discharge of the fan. The motor is enclosed in a motor casing 18^a adjoining the fan casing 18. 40

33 represents a box shaped outer casing which encloses the motor, the fan, and the 45 return conduit, and is provided with a bottom to which the motor is attached. The outer casing 33 is detachably secured to the body section of the platform between the opening 12^a and one of the external edges 50 of the body section by releasable fastenings 34, such as bolts secured to the body section and passing through openings in ears 35 on the outer casing, and clamping-nuts on the bolts. A switch 37 for starting and stopping the motor is externally located at the 55 forward end of the casing 33, so that it may be conveniently reached and manipulated. To prevent objectionable heating of the motor by heat from the tub, I provide motor-cooling means, embodied in a relatively 60 small cooling fan 40, fixed to the motor shaft at the end of the motor casing opposite that at which the air-forcing or main fan 16 is located. The motor casing 18^a 65 is provided with ventilating openings 41 and 43, arranged to receive and discharge air set in motion by the cooling fan. Said fan draws air into the motor casing at 41, forces it over the commutator at B, and through the field at C, and out of the motor casing at 70 43 as indicated by arrows in Figure 6. The outer casing 33 is provided with ventilating openings 42 and 44, adjacent to the openings 41 and 43, as shown by Figure 6. The location of the switch and the provision of motor-cooling means, as described, render the apparatus practically "fool proof," so that unskilled operators may use it without liability of having trouble. 75

The platform and the air-forcing and air-conducting means fixed thereto are applicable as a unit to any suitable tub. 80

Among the important features of the described apparatus are the following; 85

First, the location of the motor and air-forcing means above the level of the water, so that no appurtenances such as traps, check valves, etc., are required. 90

Second, the adaptability of the apparatus to an ordinary set tub, which, as is well known, is supplied with and emptied of water without manual labor. 95

Third, the air-forcing apparatus contained in a box or holder, and detachably secured as a unit to the platform. 100

I claim:

1. A washing apparatus comprising a platform, formed as a cover adapted to close the mouth of a tub, air-forcing means fixed to and located above the platform; and air-conducting means fixed to the platform and including a flow conduit, adapted to conduct air downward to the lower portion of a tub, and a return conduit adapted to conduct air upward from the upper portion of the tub, said platform and the air-forcing and air-conducting means fixed thereto being applicable as a unit to a tub. 105

2. A washing apparatus substantially as specified by claim 1, said air-forcing means including a fan casing, fixed to and bearing on the upper side of the platform, and communicating with said conduits, and an electric motor adapted to drive a fan in said casing, and located above the platform out of the path of air circulated in said conduits, so that liquid carried by the returning air through said return conduit is prevented from short-circuiting the motor. 110

3. A washing apparatus substantially as specified by claim 1, comprising also an air-distributing clothes support located below said platform, communicating with the discharge end of said flow conduit, and adapted to distribute and upwardly discharge air through clothes between the support and the platform, said support being adapted to rest on the bottom of a tub and movably connected with the flow conduit to conform to the depth of the tub. 115 120 125 130

4. In a washing apparatus, in combination, a set tub, having a waste pipe in its bottom, a platform formed as a cover adapted to close the mouth of the tub, air-forcing means including a fan casing, fixed to and located above the platform, and a motor-driven fan in said casing, air-conducting means fixed to the platform and including a flow conduit, adapted to conduct air downward from the fan casing to the lower portion of the tub, and a return conduit adapted to conduct air upward from the upper portion of the tub to the fan casing; a stand pipe communicating with the waste pipe and projecting upward therefrom to a point below and near the platform, the arrangement being such that the stand pipe releases a portion of the froth accumulating in the upper portion of the tub, and thereby maintains a uniform balance of pressure between the intake and the discharge of the

fan casing, and a screen fixed to and spaced below the platform and enclosing the intake end of the stand pipe, to prevent obstruction of the latter by fabrics in the tub. 25

5. A washing apparatus substantially as specified by claim 1, said platform including a body section provided with an opening within its margin, the said air-forcing and air-conducting means being fixed to the platform between said opening and one of the outer edges of the platform, and a displaceable section formed to cover said opening, the apparatus comprising also a screen fixed to and spaced below the displaceable section in the path of air entering said return conduit, and displaceable with said section. 30

In testimony whereof I have affixed my signature.

WILLIAM B. TUNSTALL.
